UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,378,077.

Specification of Letters Patent. Patented May 17, 1921.

Application filed February 16, 1920. Serial No. 358,836.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to buttons and particularly to that type of button wherein a metallic fastener is driven into the body of the button and permanently anchored therein.

In this type of button it is essential that 15 the metallic fastener be rigidly as well as permanently locked and anchored in place, and so held so as to prevent any slight turning or rocking movement, which might in time tend to loosen the fastener and allow 20 it to become detached from the body of the button. It is accordingly an object of my invention to provide a button of the class described wherein the fastener upon being forcibly driven through the imperforate 25 base of the button is embedded in a fibrous material, which is located in the hub, and which material not only rigidly holds the fastener against movement, but guides and directs it against the metallic anvil whereby 30 the upper extremity of the prong of the fastener is headed.

A further object is to accomplish the aforementioned ends in a simple and expeditious manner, and at the same time to provide 35 a button, which is simple in construction, light in weight, and capable of being economically produced in large quantities.

With the foregoing and other objects in view, which will appear as the description 40 proceeds, my invention resides in the novel button herein described and illustrated in the accompanying drawings, and in the combination and arrangement of parts and in the details of construction thereof, wherein 45 it is to be understood that changes may be made within the scope of what is claimed without departing from the spirit of the invention.

The preferred embodiment of my invention 50 is disclosed in the accompanying drawings, wherein:—

Figure 1 is a view in vertical longitudinal section of a button embodying the characteristic features of my invention.

Fig. 2 is a similar view, showing the fastener permanently secured in place. 55

Fig. 3 is a detail view in perspective of the non-metallic anchor of the button.

Fig. 4 is a view in vertical section of a button for use with a fastener having a 60 single prong.

Fig. 5 is a similar view, showing the metallic fastener or tack permanently anchored in place, and

Fig. 6 is a view in perspective of the 65 non-metallic anchor for this latter type of button.

Referring specifically to the several views, the button is composed of the body A, preferably formed with the downwardly projecting hub 10, and imperforate base 11, the latter being provided with the annular groove 12, adapted to receive and guide the upstanding prongs 13 of the metallic fastener therethrough. 70

Located within the hub 10 of the body is the imperforate anchor 14, preferably formed of non-metallic material, such as fiber and capable of being molded, pressed or otherwise formed to shape so as to fit 80 within the hub 10, and contact with the base throughout the entire area of the latter, and to this end the anchor is provided with the annular groove 15 corresponding to the groove 12 of the base. 85

The upper surface of the anchor extends substantially flush with the top of the hub 10 and receives thereagainst the anvil 16. A metallic cap 17 extends over the top portion of the body of the button and holds the 90 anvil 16 in place, which in turn rigidly holds the anchor 14 against movement.

In attaching the button as thus constructed the prongs of the fastener are forcibly driven through the imperforate base 11, of 95 the body, through the fibrous anchor 14, and are headed against the lower surface of the anvil 16. The upset or headed portions of the prongs as well as the body portions thereof are firmly embedded in the anchor 100 14 and accordingly are held rigidly against movement, thus insuring that the button will remain tightly secured or attached to the cloth or other material B.

In those instances where a single prong 105 fastener is to be used, I prefer to form the button as illustrated in Fig. 4, wherein the imperforate base 25 is provided with a single

and centrally located indentation or groove 26. The non-metallic anchor 27, which entirely fills the hub is formed with a corresponding groove 28, and is held in place by 5 the cap 29 and metallic anvil 30.

In this type of button, when the single prong 31 of the fastener is forcibly driven through the cloth or other material B, it is guided through the imperforate base 25 by 10 the groove 26, and passes through and embeds itself in the anchor 27, the extremity 32 of the prong being turned over and embedded within the fibrous material of the anchor as more clearly illustrated in Fig. 5.

15 From the foregoing it will be observed that I have provided a button, which may be economically produced in large quantities, is light in weight, and capable of withstanding much abuse in service, primarily 20 due to the manner in which the anchor not only holds the fastener rigidly against movement, but also due to the manner in which it supports the entire hub of the button and prevents it from being crushed or 25 collapsed.

Having thus described my invention, what I claim is:—

1. A button comprising a body, including a hub having an imperforate base and

provided with a groove therein, an imperforate non-metallic anchor fitting within and substantially filling said hub. 30

2. A button of the class described comprising a body including a hub and an imperforate base with a groove therein, a non-metallic anchor located within said hub having a groove therein corresponding to the groove of the said base and an anvil within the body of said button and adapted to 35 head the prong of a fastener against said anchor. 40

3. A button comprising a body including a hub having an imperforate base and provided with an angular groove therein, an imperforate non-metallic anchor fitting 45 within and substantially filling said hub, and an anvil located within said body adjacent said anchor and coöperating therewith for the permanent securement of the fastener to the body of the button. 50

Signed at Waterbury, in the county of New Haven, and State of Connecticut, this 11th day of Feb. A. D. 1920.

FRANKLIN R. WHITE.
